UNITED STATES PATENT OFFICE

HUGO J. MOSER, OF SALT LAKE CITY, UTAH

COUNTER

Application filed January 31, 1930. Serial No. 424,824.

This invention relates to an improvement in a counter, and more particularly to a lunch or soda fountain counter.

The object of this invention is to provide a counter having a receptacle in the outer face thereof and placed below the forward projection of the top of the counter, in such a manner that a lady being served at the counter, if she so desires, may place her purse 5 therein or any package she may be carrying, thus abolishing the necessity of holding the purse on her arm or placing it on the counter while being served.

With this object in view the invention consists of certain novel features of construction to be hereinafter fully described and claimed.

In the accompanying drawing forming a part of this specification and in which corresponding parts are denoted by like reference characters, is illustrated the preferred form of embodiment of the invention capable of carrying the same into practical use, it being understood that the invention is not necessarily limited thereto, as various changes in shape and proportions and general assemblage of its construction may be resorted to without departing from the principles of the invention, or sacrificing any of its advantages, and the right is therefore reserved for making all changes and modifications which will fall within the scope of the invention.

Referring to the drawing:

Figure 1 is a front view of the preferred form of the invention showing the receptacles 1 constructed within the counter face.

Fig. 2 is a view through line 2—2 Fig. 1.

Fig. 3 is a front view of a counter showing 40 the receptacle secured to the counter.

Fig. 4 is a view through 4—4 Fig. 3.

The counter may be constructed with a tile front or of any other material desired.

The invention comprises a counter having 45 a front wall A, a back wall B and a top C.

On the front wall A at the upper edge there-of is a projection 5. Below the projection 5 and spaced therefrom is another projection 6. The projections 5 and 6 extend the full length of the counter.

Placed between said projections 5 and 6 at the end thereof are blocks 7 which form the corner blocks of the counter. Spaced away from the blocks 7 are other blocks 8, and spaced away from the blocks 8 are other blocks 9. The blocks are so placed between the projections 5 and 6 to the full length of the counter. When the blocks are so placed they form the end walls of compartments 14, 15 and 16 which when so constructed form individual receptacles into which a lady may place her purse if she so desired. The blocks may be omitted and the projection 6 forming a continuous shelf upon which packages may be placed. The blocks are 65 preferable as they form partitions between each compartment in such a manner that a party resting upon one chair will not be able to remove a package from a compartment in front of another party resting upon a chair 70 next to him without said party knowing it. The chairs upon which the parties rest while being served are placed in alinement of one of the compartments.

The design in Figs. 3 and 4 shows compartments 1a attached to a counter by means of bolts 12. These compartments are only used where a counter is now in use and when the owner of the counter wishes them placed onto the counter.

The counter is constructed in sections to the length desired, and the ends are formed by a section of the required length.

Having thus described the invention what I claim as new and desire to secure by Letters Patent, is:

1. In a counter having a front wall a back wall and a top, said front wall having a projection near the upper edge thereof and another projection below said projection and 90

spaced away from said upper projection, blocks placed between said projections, said blocks being spaced apart to form compartments therebetween, said compartments for receiving packages therein.

2. In a counter having a side wall a back wall and a top, said front wall having projections thereon near the upper edge thereof, said projections being spaced apart and having blocks therebetween placed in such a manner to form compartments between said projections and said blocks, all substantially as set forth.

HUGO J. MOSER.
